UNITED STATES PATENT OFFICE.

SAMUEL OLDHAM, OF PHILADELPHIA, PENNSYLVANIA, ASSIGNOR TO GEORGE OLDHAM AND SON COMPANY, OF PHILADELPHIA, PENNSYLVANIA, A CORPORATION OF PENNSYLVANIA.

TOOL RETAINER.

Application filed April 15, 1920, Serial No. 374,116. Renewed September 29, 1922. Serial No. 591,398.

To all whom it may concern:

Be it known that SAMUEL OLDHAM, a citizen of the United States, residing at Philadelphia, in the county of Philadelphia and 5 State of Pennsylvania, has invented certain new and useful Improvements in Tool Retainers, of which the following is a specification.

This invention relates to an improved tool 10 retainer for holding working tools at the operating ends of pneumatically-operated hammers.

Various forms of clips have heretofore 15 been provided to effect a loose coupling of the working tool with the end of the hammer-barrel and the simplest of these forms which have come into commercial use are those which spring into engagement with both the barrel and the working-tool. In 20 practice, these spring clips seldom remain in place and are readily shot from the end of the barrel when the percussion plunger strikes the working-tool while the latter is withdrawn from the work. This displacement 25 of the clip results from the fact that the clips are usually of the split-band type to enable both ends to be sprung as they are snapped into engagement with the barrel and the tool and such bands will as readily 30 spring to disengage as they will to engage the barrel and tool.

My invention has for its object to provide 35 an improved construction of tool-retainer whereby the tendency of the working-tool to pass from one end of the retainer will cause the other end of the retainer to more closely clamp the hammer-barrel.

The invention is illustrated in the accompanying drawing, wherein,—

40 Fig. 1 shows the lower end of a hammer-barrel, the working-tool and the improved retainer in place to couple the same together.

Fig. 2 illustrates the end of the hammer-barrel and the improved retainer,—the latter having a position to enable it to be attached to or detached from the barrel.

Fig. 3 shows the detached retainer in side elevation, and

Fig. 4 illustrates the same in top or plan 50 view.

Referring now to the drawing the numeral 5, designates the operating or tool-end of a pneumatic hammer barrel which latter has an annular groove 6, which produces an

upper shoulder 7 and a lower shoulder 8 thereon. From the lower shoulder 8 down, the barrel in this instance, is tapered to form a nozzle-like lower end 9.

The interior of the barrel is of the usual and well-known form with a passage therein for the entrance of one end of a working-tool so that a plunger on the interior of the barrel may reciprocate and deliver, in rapid succession, blows on the inner end of the working tool.

The working-tool 10, in the present instance has the form of a rivet-set, but obviously may have a form to accomplish other work, such for example as a chisel.

In the present instance this tool is illustrated as having a head 11; two spaced-apart annular shoulders 12 and 13 whereby to form between them a reduced neck 14, and a shank 15 which enters the nozzle-end 9, of the barrel as shown in broken lines in Fig. 1 of the drawing.

The present invention is designed to loosely couple the rivet-set or working-tool 10, with the barrel of the pneumatic hammer so as to retain the tool in position but permit it to have longitudinal movement with respect to the barrel-end.

The retainer comprises two semi-circular members 16 and 17 respectively which have ends 18, that are lapped and pivotally connected, as for example, by means of rivets 19. When thus riveted together the two connected members form a two part cylindrical coupling which tapers in a vertical direction.

At the larger end, each retainer member is provided with an inturned segmental flange 20, while at the smaller end each member is provided with vertical notches 21—22 whereby to form a plurality of yielding prongs 23, each having an inwardly-projecting shoulder 24 thereon, for a purpose that will presently be explained.

In the present instance I have provided the lapped ends of the retainer members with locking means whereby to hold the two members in a normal operating position such as they assume when in place on the end of the tool-barrel.

As illustrated in Figs. 1-2 and 4 of the drawing the locking means comprises an outwardly-projecting bump or lug 25, on the upper and lower edges of the underlapping

end of the members both above and below the pivot 19, and a bump or lug on the upper and lower edges of the overlapping end of the members whereby to produce a cavity 5 or recess 26, at the inner face thereof. These projections and recesses on the underlapping and overlapping ends of the members are so located with respect to the pivot 19, that when the two members are rocked on 10 said pivot so as to bring the lugs 25 and recesses 26 into alinement, the two may snap into locking engagement and thereby hold the members in the engaging position, as will presently be more fully explained.

15 The operation of attaching the coupling is best illustrated in Fig. 2, of the drawing wherein it will be seen that the two members have been rocked on the pivot 19, so as to draw or contract the lower prong-end 23, thereby reducing the diameter of said lower 20 end while spreading or expanding the upper flanged-ends to increase the diameter of the latter between the inturned-flanges 20 on the two members.

25 Having thus spread the upper flanged-ends of the two members the latter end may be fitted around and in alinement with the groove 6 on the hammer-barrel whereupon by rocking the members on the pivot 19, the upper flanged ends may be contracted until the flanges 20, project into the annular groove 6 and lock the coupling or retainer in place on the end of the barrel. Upon completing this contracting operation, the lugs 25, and recesses 26 will be brought into engagement and the two members thereby locked in the retained position on the barrel.

30 The tool 10, may then be inserted in the barrel,—the shank-end 15, passing up freely through the yielding of prongs 23, and the latter then yielding and spreading outwardly as the upper shoulder 13, is forced past the prongs. When the upper shoulder 45 13, has passed the yielding prongs 23, the latter will close or contract about the reduced neck 14, of the tool between the lower shoulder 12 and the upper shoulder 13, so that the tool may have a longitudinal movement equal to the distance between the shoulders 12—13 but will be limited in such movement by said shoulders.

50 It will be noted that any tendency of the tool to force its way outwardly past the yielding prongs 23, will cause shoulder 13, to press outwardly on the prong-shoulders 24, and thereby tend to further contract the upper flanged ends of the members and increase the grip of the flanges 20, about the groove 6 and above the lower shoulder 8, on the nozzle-end of the barrel.

Having described my invention, I claim,—

1. A working-tool retainer for pneumatic tools said retainer comprising a plurality of pivotally-connected segments with

flange-means at the upper end of the connected segments and yielding means at the lower end thereof said segments being capable of rocking on their pivot connections whereby to move the flange-means toward 70 or from each other.

2. A working-tool retainer for pneumatic tools said retainer being composed of a plurality of pivoted-together segments with flange means carried by the segments 75 above the pivot means and with yielding means circumferentially arranged on the segments below said pivot-means whereby the spreading of the lower yielding means will move the upper flange-means toward 80 each other.

3. A working-tool retainer for pneumatic tools said retainer comprising a plurality of segments with the end of one segment lapping the end of the next segment 85 and the lapped portions of the segments being pivotally connected whereby to form an annular retainer and said retainer having inwardly projecting engaging devices both above and below the pivots. 90

4. A working-tool retainer for pneumatic tools comprising a plurality of segments larger at one end than the other and each having an inturned flange at its larger end and an inwardly-projecting shoulder 95 near its smaller end, means for pivotally connecting the segments between their larger and smaller ends whereby when the smaller ends are drawn together the larger ends will be spread apart. 100

5. A working-tool retainer for pneumatic tools comprising a plurality of segments each having both ends circumferentially pivoted to another segment and each segment having an inturned flange at its 105 upper edge above the pivots and a yielding prong at its lower end below the pivots.

6. A working-tool retainer for pneumatic tools comprising a plurality of segmental members each member having an 110 end that laps and is pivotally connected to another member-end and each member below its pivot being notched and each of said members being provided with a circumferential inturned flange above its pivot and an inwardly-projecting shoulder below its pivot. 115

7. A working-tool retainer for pneumatic tools comprising a plurality of segmental members whose ends are pivotally 120 connected and each member being larger at the top than the bottom edge.—the larger edge of each member being provided with an inwardly-extending flange and below the pivots and near the smaller edge each member having an inwardly-extending shoulder whereby when the shouldered portions of the members are contracted the flanged upper portions will be swung outwardly. 125

8. A working-tool retainer for pneu- 130

matic tools comprising a plurality of segmental members having lapped and pivotally-connected ends with inwardly-extending engaging means above and below the 5 pivots and locking means on the lapped ends adjacent to the pivots.

9. A working-tool retainer for pneumatic tools comprising a plurality of segmental members having lapped and pivotally-connected ends with inwardly-extending engaging means above and below the 10 pivots and locking means on the lapped ends of the members both above and below the said pivots.

15 10. A working-tool retainer for pneumatic tools comprising two segmental members together forming a circular retainer said members being permanently pivoted

together at diametrically opposite sides, each member having an inturned flange 20 above its pivot connections and an inturned shoulder below its pivot connections and at said shoulders the members being formed to yield.

11. The combination with a cylinder or 25 barrel having a locking groove thereon, of a removable working tool insertable in the end of said barrel and provided with an exterior shoulder, and a retainer comprising members with inturned shoulders at the upper 30 end and yielding means near the lower end said members being pivotally connected at a plurality of points around their circumference.

In testimony whereof I affix my signature. 35
SAMUEL OLDHAM.
